(57) **CLAIM**

The ornamental design for a metronome, substantially as shown and described.

DESCRIPTION

FIG. 1 is a top perspective view of our metronome.

FIG. 2 is a front view of our metronome.

FIG. 3 is a back view of our metronome.

FIG. 4 is a left side view of our metronome.

FIG. 5 is a right side view of our metronome.

FIG. 6 is a top view of our metronome.

FIG. 7 is a bottom view of our metronome; and,

FIG. 8 is a bottom perspective view of our metronome.

The dashed lines represent a boundary of the claimed design and are not themselves part of the claimed design.
